HAIR DRIER

John F. Saye, Powersite, Mo.

Application May 31, 1947, Serial No. 751,523

3 Claims. (Cl. 34—99)

1

My invention relates to a hair dryer, more particularly for use in combination with conventional vacuum cleaner and the objects of my invention are:

First, to provide a hair dryer of this class, which is readily connected with a conventional vacuum cleaner whereby a person's hair may be aerated and dried by the circulation of air therethrough by said vacuum cleaner;

Second, to provide a hair dryer of this class having a helmet arranged to be placed over a person's head at the hair line which causes warm air to be circulated through a person's hair and prevents cool air from being drawn into said helmet whereby a person's hair may be dried quickly and efficiently;

Third, to provide a hair dryer of this class having a helmet in which the air is introduced near the hair line of a person's scalp and drawn upwardly through the hair causing continuous passage of fresh warm air through said hair which saves much time in the hair drying process;

Fourth, to provide a hair dryer of this class which may be very readily and easily installed in connection with the upper edge of a door and vertically adjusted to suit the particular position of the patient whose hair is being dried;

Fifth, to provide a hair dryer of this class having a vacuum tube forming a pivotal bearing for the dryer which permits said dryer to be pivoted from a horizontal position to a vertical position when clearance thereunder is required;

Sixth, to provide a hair dryer of this class in which vacuum created by a conventional vacuum cleaner draws air through a heating element, then into the hair drying helmet and outwardly thereof providing a very simple arrangement for heating and delivering the air to the hair of the patron; and

Seventh, to provide a hair dryer of this class which is very simple and economical of construction, efficient in operation and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon forming a part of this application in which:

Fig. 1 is a top or plan view of my hair dryer showing portions thereof broken away to facilitate the illustration; Fig. 2 is a side elevational

2

view thereof showing portions broken away and in section to amplify the illustration; Fig. 3 is an enlarged fragmentary sectional view taken from the line 3—3 of Fig. 2; Fig. 4 is a sectional view taken from the line 4—4 of Fig. 2 showing by dash lines a fragmentary portion of a door on which my hair dryer is supported; and Fig. 5 is an enlarged fragmentary sectional view taken from the line 5—5 of Fig. 2.

Similar characters of reference refer to similar parts and portions throughout the several views of the drawings.

The helmet 1, vacuum tube 2, helmet casing 3, heater tube 4, heating element 5, vacuum tube adapter 6, bearings 7, bracket 8, hanger 9, switch 10, clamps 11, helmet skirt 12 and the vacuum cleaner hose 13 constitute the principal parts and portions of my hair dryer.

The helmet 1 is a hollow dome-shaped member preferably made of sheet metal and is provided with a channel-shaped annular lower edge portion 1a adapted to provide a support for the lower skirt edge 3a of the helmet casing 3 which surrounds said helmet 1 and encloses the space inwardly of the periphery of the channel-shaped portion 1a communicating with the holes 1b near the lower edge 1c of the helmet 1. The normally upper end of the helmet 1 is provided with an outlet opening 1d which is surrounded by the helmet casing 3, as shown best in Fig. 5 of the drawings. The outlet opening 1d of the helmet 1 is defined by an extruded tubular portion 1e fitted in the opening 3b in the helmet casing 3. Internally of the extruded portion 1e in the opening 1d of the helmet 1 is the vacuum tube 2. This vacuum tube 2 extends horizontally to the bracket 8 upon which said vacuum tube 2 is pivotally mounted by means of the U-shaped bearing members 7. The bracket 8 is vertically slidably mounted on the hanger 9 and this bracket 8, as shown in Fig. 1 of the drawings, is provided with U-shaped clip portions 8a at opposite edges clipped over the hanger 9 which is a substantially flat rectangular member having a flat clip 9a at its upper end and is also provided with a row of holes 9b centrally thereof engageable by the screw 8b in connection with the bracket 8 whereby said bracket 8 may be vertically adjustably fixed in connection with said hanger 9 and the clip 9a of the hanger 9 is adapted to fit over the upper edge of a door or other member for supporting my hair dryer. The opposite end of the vacuum tube 2 from the helmet 1, is provided with a vacuum tube adapter 6 which is arranged to receive one end of a conventional vacuum

cleaner intake tube 13. Secured by means of the clamps 11 to the vacuum tube 2 is the heater tube 4. This heater tube 4 is a hollow cylindrical tube provided with an annular row of openings 4a therein arranged to admit air, as indicated by arrows in Fig. 2 of the drawings, around the heating element 5. This heating element 5 is a conventional electrical heating element of the conical type having convolutions of resistance wire disposed thereon. The base 5a of the heating element 5 encloses the extending end of the heater tube 4. This heater tube 4, as shown in Fig. 2 of the drawings, communicates with the interior of the helmet casing 3 outwardly of the openings 1b in the helmet 1. The helmet skirt 12 is secured to the outer side of the helmet casing 3 adjacent the lower edge 1c of the helmet 1 and extends downwardly in annular form a certain distance below the lower edge 1c of the helmet 1 and is provided with a contracting band portion 12a arranged to fit over a person's head in contiguous relationship therewith at the hairline of the person's scalp.

° The operation of my hair dryer is substantially as follows:

When the vacuum cleaner tube 13 communicates with the vacuum tube 2 and the vacuum cleaner is operating, air passes inwardly through the openings 4a in the heater tube 4 around the heating element 5 which heats the air, then the air passes inwardly into the helmet casing 3 and downwardly around the helmet 1 through the holes 1b and upwardly into the vacuum tube 2 and then passes into the vacuum cleaner to which the vacuum cleaner hose 13 is connected. It will be here noted that the warm air passing from the heating element 5 through the heater tube 4 into the casing 3 and through the opening 1b passes from the lower portion of a person's scalp upwardly and around the person's head through the wet hair whereby the air is forced to travel through the hair instead of traveling around it. The helmet skirt 12 effectively seals the air passage around the person's head preventing cold air from entering the helmet 1, thus the effectiveness of the warm air passing through the openings 1b and into the person's hair is maintained. It will be noted that the helmet 1, helmet casing 3 and helmet skirt 12 are positioned on an angle substantially corresponding to the angular relationship of a person's hair line so that said person may sit naturally and comfortably during the hair drying operation performed by my hair dryer. The vertical adjustment of my hair dryer, by means of the bracket 8 having the screw 8b engageable with the openings 9b of the hanger 9 provides vertical adjustment to accommodate various elevations at which the heads of various persons may be disposed. The hanger 9 having the clip 9a provides convenience in mounting my hair dryer on a conventional door and in the event overhead clearance is required, the vacuum tube 2 together with the helmet casing 3 and all connecting parts may be pivoted upwardly into substantially parallel relationship with the door whereby my hair dryer is out of the way. In connection with the heating element 5, the switch 10 is employed to energize the heating element 5 electrically and is readily and easily controlled.

Though I have shown and described a particular construction, combination and arrangement of parts and portions, I do not wish to be limited to this particular construction, combination and arrangement, but desire to include in

the scope of my invention the construction, combination and arrangement substantially as set forth in the appended claims.

Having thus described my invention, what I claim as new and desire to secure by Letters Patent is:

1. In a hair dryer of the class described, the combination of a helmet having openings therein near its lower edge, a casing surrounding said helmet in substantially air tight relationship communicating with said openings, a heater tube communicating with the interior of said casing, a heating element in said tube, openings in said tube surrounding said heating element arranged to admit air adjacent said heating element, a vacuum tube communicating with the upper middle portion of said helmet, a vacuum cleaner hose in connection with said vacuum tube for creating an air draft through said heater tube around said heating element into said casing through the openings in said helmet and outwardly through said vacuum tube and vacuum cleaner hose, a helmet skirt in air tight relationship with the lower portion of said helmet extending downwardly therefrom and provided with a contracting band portion arranged to be fitted around a person's scalp adjacent the hair line thereof, said vacuum tube disposed on substantially a horizontal plane, bearing means for supporting said vacuum tube, a bracket to which said bearing means is connected and a hanger on which said bracket is vertically adjustably mounted, said hanger having a clip portion at its upper end adapted to be fitted over the upper edge of a door.
2. In a hair dryer of the class described, a helmet substantially dome-shaped and having openings therein near the lower edge thereof, a casing surrounding said helmet defining an enclosed air space outwardly of said helmet, a vacuum tube communicating with the interior of said helmet arranged to move air through said openings in said helmet and outwardly thereof, heating means communicating with said casing arranged to supply warm air outwardly of said helmet communicating with said openings therein, said heating means including a tube having openings therein, a heating element inwardly of said openings arranged to heat air passing through said openings in said heating tube, said vacuum tube disposed on a substantially horizontal plane and having an angularly disposed end portion, a bracket for supporting said angularly disposed end portion to which said vacuum tube is pivoted, and a hanger on which said bracket is vertically adjustably mounted.
3. In a hair dryer of the class described, a helmet substantially dome-shaped and having openings therein near the lower edge thereof, a casing surrounding said helmet defining an enclosed air space outwardly of said helmet, a vacuum tube communicating with the interior of said helmet arranged to move air through said openings in said helmet and outwardly thereof, heating means communicating with said casing arranged to supply warm air outwardly of said helmet communicating with said openings therein, said heating means including a tube having openings therein, a heating element inwardly of said openings arranged to heat air passing through said openings in said heating tube, said vacuum tube disposed on a substantially horizontal plane and having an angularly disposed end portion, a bracket for supporting said angularly disposed end portion to which said vacuum tube is pivoted, and a hanger on which said bracket is vertically adjustably mounted.

mounted, said hanger provided with a substantially U-shaped in cross section clip portion arranged to engage the upper edge of a door.

JOHN F. SAYE.
